METHOD FOR STABILIZING SOYBEAN OIL
REFINED BY SOLVENT TREATMENTHerbert J. Passino, Englewood, N. J., assignor to
The M. W. Kellogg Company, Jersey City, N. J.,
a corporation of Delaware

Application October 2, 1948, Serial No. 52,535

11 Claims. (Cl. 260—426)

1

This invention relates to the refining of soybean oil and more particularly to a solvent treatment of soybean oil to produce an improved soybean oil product. In its most generic form, the method of the invention involves solvent fractionating soybean oil with a propane-type solvent at a temperature near the critical temperature in order to obtain an extract fraction containing the bulk of the soybean oil, and a small raffinate fraction containing, along with color bodies etc., substances which profoundly affect the chemical stability of the oil; and adding to the extract oil a small portion of the raffinate, preferably enough to give the soybean oil product satisfactory stability without appreciably darkening its color. Species and sub-species of the invention provide for additional coacting steps to obtain a portion of the raffinate having optimum stabilizing characteristics with a minimum of color bodies or other impurities, and to treatment of the extract oil which can best be carried out in the absence of the raffinitic stabilizing agents. Novel compositions of matter are produced by the various refining methods; these are comprised of a propane extract of soybean oil to which has been added stabilizing agents from the raffinate.

This application is a continuation-in-part of copending U. S. application Serial No. 699,320 of the same inventor.

Heretofore the processing of crude soybean oil has generally involved water washing of the crude oil to remove phosphatides, and then alkali treatment to remove fatty acids and residual phosphatides; the alkali treatment is usually followed by further washing, bleaching with clay, and deodorization with steam. In the course of refining, there is a loss of oil which is roughly proportionate to the quantities of the various impurities; for example, the loss increases with increasing amounts of fatty acids which it is necessary to neutralize in the alkali step; with high grade crude oils having an exceptionally low fatty acid content, losses may be confined to between three and five per cent, but with lower grade and less expensive oils containing between three and eight per cent of fatty acids, as much as eight to fifteen per cent of the oil may be lost. The product oil has fair stability, a light yellow color, and contains traces of soap which tend to produce side reactions which eventually cause deterioration in taste.

It is a major object of the present invention to refine soybean oil with substantially smaller losses and to produce a refined product superior in stability, taste, and color to refined oil heretofore known. A related process has previously

been proposed in application Serial No. 699,320 of the same inventor; that application describes the refining of soybean oil by combining the solvent fractionation step with steam stripping. In the first step color bodies, phosphatides, fatty acids of high molecular weight (and hence high boiling point) were precipitated into a small raffinate by fractionation of the crude oil with propane or a similar solvent under elevated temperatures and pressures; the second step of steam stripping removes the coloring matter, fatty acids, etc. which remain. The two steps neatly complement each other since the impurities are almost all either relatively insoluble in propane or relatively volatile, so that those not eliminated by one step are by the other.

The solvent fractionation required for the process of the present invention is of the so-called paracritical type described previously in the aforesaid application Serial No. 699,320. The solvent employed is one having a critical temperature much lower than that at which the soybean oil tends to deteriorate rapidly; moreover, the critical temperature of the solvent is preferably sufficiently low so that it can be separated from the product oil at the temperature of steam usually available in commercial plants. Such solvents have a critical temperature not greater than about 450° F. and most of them are gaseous at ordinary temperatures and pressures. The solvents of the type described present unusual advantages in obtaining a cut comprising any desired proportion of the fractionated oil. The density of a solvent (and hence its solvent power) decreases as its critical temperature is approached; if the solvent contains a solute of higher critical temperature, i. e. the critical temperature of the mixture may exceed the critical temperature of the solvent by a few degrees, but it nevertheless remains true that as the critical temperature of the solvent is approached (and, in some cases passed) the solvent tends to precipitate its solute into a lower phase comprised of solute diluted with a very different and much smaller proportion of the solvent. In the fractionation of crude soybean oil with propane, for example, a mixture of 15 parts of propane with one part of soybean oil at a temperature of about 150° F. (and under a liquefying pressure of about 325 pounds per square inch gage) two phases are formed; almost all of the propane and almost all of the soybean oil mix to form a light extract phase but a very small proportion of the soybean oil, usually about one or two per cent precipitates as a heavier raffinate phase, which contains a much smaller proportion of propane than the extract phase. At a temperature of 210° F. and under adequate

3

liquefying pressure (about 615 pounds per square inch gage), the composition of extract and raffinate radically shifts; under equilibrium conditions, most of the soybean oil is now in the raffinate. By selecting the appropriate temperature within the range between the temperature of maximum miscibility of the oil and propane and the critical temperature of the oil-propane mixture, almost any desired fractionation can be accomplished. Although this fractionation can be achieved in a batch process, it is much more satisfactory both from the standpoint of accuracy and commercial practicability to carry out the fractionation continuously in a vertical fractionation tower in which the propane and oil are countercurrently contacted. A particularly satisfactory form of such a tower is one in which there is a propane inlet and a raffinate phase outlet at the bottom, an extract phase outlet and reflux inlet near the top, and a charge oil inlet in the middle portion. In such a tower solvent flowing upwardly from the solvent inlet dissolves most of the oil flowing downwardly from the charge oil inlet; raffinate phase accumulates in the bottom of the tower and the extract phase is continuously withdrawn from the extract phase outlet at the top; the solvent content of the extract phase is reduced and some of it is returned to the tower through the reflux inlet and flows downwardly in countercurrent contact with the upflowing extract phase; in this contact between downflowing reflux liquid and upflowing extract phase, the latter tends to become enriched in the more soluble oil components and to precipitate less soluble oil components, a process well known to those familiar with the art of solvent fractionation and fractional distillation as "rectification." In solvent fractionation under paracritical conditions the entire tower may be at a single temperature in the paracritical range and reflux liquid introduced through the reflux oil inlet may be the sole means of rectifying the extract phase. However, it is also possible to rectify the extract phase by establishing a temperature gradient within the upper part of the fractionation tower so that the temperature increases with increasing elevation; under these conditions, a larger fraction of the oil than is required is at first dissolved into the extract phase but precipitation occurs as it flows upwardly to regions of higher temperature until only the desired fraction remains in the extract phase withdrawn at the extract phase outlet. The liquid precipitated by the upflowing extract phase serves as reflux liquid as it flows downwardly through the fractionation tower. Rectification of the upflowing extract phase may be accomplished by either the return of the reflux liquid to the tower or by the temperature gradient method alone or by both methods used simultaneously.

Although a fraction comprising almost any desired proportion of the charge oil may be obtained by control of the paracritical temperature, refluxing, solvent ratio, etc., control of the chemical composition of the fractions is limited to sorting out the more soluble from the less soluble components so that it may happen, as in the case of soybean oil, that two components which it would be desirable, for commercial reasons, to keep together are separated into the two different fractions. In soybean oil refining, it is desirable to eliminate the color bodies, phosphatides, fatty acids and certain constituents present in minute quantity which cause bad taste or odor. As described in my copending application Serial No. 75

699,320, this is very successfully done by propane fractionation and steam treatment. However, the clear, odorless, and sweet tasting oil produced by this process has lost some of the natural preservatives which are present in the crude oil. These substances are present in the crude oil in a very small percentage but are extremely effective in protecting the oil from oxidation by the air; from polymerization, conjugation, etc., under the influence of heat; and in general, from any reaction which tends to slowly degrade the oil upon standing, especially in the presence of air or under temperatures slightly above usual room temperatures. The precise nature of these inhibiting substances is not known but there appears to be several of them having a variety of inhibiting effects. They will all be referred to herein as stabilizing agents; this term includes particularly but not merely antioxidants; it also includes other components which prevent degradation due to polymerization, conjugation and the like. All methods of refining involve the loss of some of these stabilizing agents, and although the refined oil may be satisfactory for many commercial purposes, the present invention provides a means for producing a refined oil of superior stability. For example, refined oils may be subjected to an oven test in which they are stored at a temperature of 140° F. for several days; all refined oils eventually deteriorate in taste, apparently as the result of oxidative deterioration, but the deterioration is markedly slower in the case of oils refined by the method herein disclosed. This method is based upon the discovery that stabilizing agents from a crude oil tend to concentrate in the raffinate from a propane fractionation, and that the refined oil obtained from the extract phase can be made unusually stable by the addition of a small portion of the raffinate. Naturally, some of the undesirable color bodies and other impurities are thus returned to the oil, but so small a quantity of raffinate is required in order to endow the refined oil with optimum keeping qualities that the disadvantages are not serious. Excellent stability can usually be achieved by adding about one-tenth of the raffinate, without further treatment, to the refined oil. Refined oil is darkened slightly by such treatment; but the raffinate may be treated and washed with such solvents as acetone and alcohol, to obtain a precipitate which is a light tan and which may be added, in whole or in part, without visibly effecting the color or clarity.

Among the stabilizing agents are some which have been found to be so sensitive to heat that they darken the oil if present therein during steam stripping. It is an advantage of the present invention that the extract fraction, which comprises almost all of the crude soybean oil may be subjected to extensive steam stripping after the heat sensitive stabilizing agents have been separated by propane fractionation and before any of them have been returned to the oil from the fractionation raffinate. Steam treatment of the extract not only removes the last traces of the propane solvent but also eliminates volatile impurities such as the lighter fatty acids, and certain impurities which adversely affect taste and color. For six hours with ten per cent steam at temperatures as high as 475° F. steam stripping may be carried out with only beneficial effects. The resulting oil is better tasting and slightly clearer in color than before the stripping operation. A small quantity of the stabilizing agents

may then be added to the oil to produce a refined product of superior quality.

The accompanying drawing shows diagrammatically a refining system employing the method of the present invention. Crude soybean oil is charged through line 10 to a continuous countercurrent fractionation tower 11 in which it is fractionated with the preferred solvent, propane, introduced to the lower end of tower 11 through line 12. Within the tower, predetermined paracritical conditions are maintained by controlling the temperature and pressure of the oil and propane charged, and also by heating means 13 and refluxing means 14. In the present example it is desired to fractionate the oil-propane mixture into a seventy-five per cent extract phase and a twenty-five per cent raffinate phase. The raffinate phase in tower 11 is pumped by pump 15 through line 16 and heater 17 to a second continuous countercurrent fractionation tower 18 supplied with additional propane through line 19. In second tower 18 the raffinate is fractionated under slightly different paracritical conditions to obtain an overhead at 20 comprising about twenty-three per cent of the original crude oil, and a dark jelly raffinate at 21 comprising about two per cent of the crude oil. The purpose of the two tower fractionation in the example disclosed is to obtain from the raw soybean oil a fraction comprised of the relatively more saturated glycerides suitable for food purposes (i.e. seventy-five per cent extract from tower 11), and a fraction of relatively unsaturated glycerides most suitable for paint drying oils, (i.e. the twenty-three per cent extract taken from tower 18). Thus two different refined oils are obtained. Ordinarily the paint oil does not require additional treatment. If no paint oil fraction is desired, only one tower need be operated, and the overhead extract may contain between ninety and ninety-nine per cent of the crude oil; or both tower 11 and tower 18 may be employed and the two overheads mixed by opening valve 22; this type of operation employs the two towers to achieve one tower operation; some advantage is gained in that a satisfactory fractionation is accomplished with somewhat less propane.

The food oil fraction (either the overhead from tower 11, or both the overhead of tower 11 and tower 18, if no paint oil fraction is desired) is transferred through line 23 to be diverted by valves 24 and 25 either to treatment for salad and cooking oil purposes, or to treatment to produce a margarine or shortening. In the former case, the oil is subjected to the steam stripping process referred to in the trade as steam deodor-

ization by conventional steam deodorization means 26. The deodorized salad and cooking oil is withdrawn through line 27 after the addition of a small quantity of stabilizing agents obtained in a manner described hereinafter. Margarine or shortening is produced by hydrogenation at 28 followed by steam deodorization at 29, and the addition of stabilizing agents to produce the finished product at 30.

The stabilizing agents are preferably obtained from the raffinate withdrawn through tower 18 to line 21 by first subjecting it to acetone extraction at 31 to separate it into acetone solubles 32 and acetone insolubles 33. The acetone insolubles usually comprise about two-thirds of the treated raffinate. The acetone insolubles are next washed or extracted with alcohol in an alcohol extraction step 34, and separated into alcohol solubles 35 and alcohol insolubles 36. The alcohol insolubles will usually be found to contain sufficient stabilizing agents and very little coloring matter, and may be transferred through lines 37, 38 and 39 to the oil or shortening of lines 27 and 30 respectively. Sometimes oven tests of products obtained from particular oils may suggest the desirability of returning the greater portion of the raffinate stabilizing agents to the refined oil. A small quantity of untreated raffinate, or of acetone insolubles which has not been alcohol treated may be added to the refined oil by means of lines 40 and 41 respectively, when the results demonstrate the desirability of doing so.

Typical process conditions for refining soybean oil in accordance with the present method are given herewith:

Propane/oil ratio	15-1 (vol.)
Tower height overall	60 ft.
Stripper	Not less than 10 ft.
Rectifier	Not less than 40 ft.
Reflux ratio	0.6-0.8.
Temperature gradient	5° F. (rectifier).
Final stripping	Equivalent to 2 hours, 13% steam/hr. at 2 mm. Hg abs., 425° F.

In a typical single tower operation ninety-eight per cent of the oil is taken overhead and the two per cent raffinate is treated with acetone to obtain acetone insolubles; acetone insolubles amounting to about one-tenth of one per cent of the original oil is then added to the refined oil after steam stripping.

The effect of adding various portions from the bottoms fraction before and after steam treatment is shown in the following chart:

Table.—Processing of soybean oil

In the table color symbols are based on Lovibond color notation.

The stabilizing effect can be accomplished in some degree with an unselectd portion of the raffinate; however, much better results follow from treating the raffinate to obtain a selected portion which contains a concentrate of the stabilizing agents and a minimum of color bodies. In the example, acetone insolubles or, more broadly, ketone insolubles are employed. There are other methods of obtaining a satisfactory selected portion of the raffinate, however. It has been found that a concentrate of stabilizing agents may be separated from the raffinate by chilling the raffinate in the presence of a solvent diluent such as hexane or propane; the extent of chilling necessary to obtain a suitable stabilizing agent fraction will vary from oil to oil, and a sample must be tested in order to determine just how much of a precipitate should be chilled out; 15

chilling temperatures generally fall in the range between 0° F. and -40° F. Another method of treating soybean oil raffinate to obtain a concentrate of stabilizing agent involves contacting the raffinate with an aqueous caustic solution and washing the remaining mixture with water to separate an oil scum from the water soluble constituents; the oil scum is found to contain a concentrate of stabilizing agents.

One of the advantages of the present process is that it makes possible extensive steam treatment of the soybean oil when it is in its intermediate condition after decolorization but before addition of stabilizing agents. In this intermediate condition the oil is generally treated with steam in a temperature range between 350° F. and 450° F. for a period of between one and five hours with between five and twenty per cent of steam under a vacuum of between two and twenty mm. of mercury to strip it of volatile components.

It is, of course, possible to subject the stabilizing agent portion of the raffinate to various decolorizing treatments in order to reduce to a minimum the coloring effects of adding it to the refined soybean oil. For example, this portion may be contacted with a clay or activated charcoal; or it may be chemically treated with such bleaching agents as chlorine dioxide, hydrogen peroxide, etc.

I claim:

1. A method of refining soybean oil which includes the steps of: intimately contacting said soybean oil with a solvent having a critical temperature of less than 450° F. under liquefying pressure and in the paracritical range of the solvent-oil mixture to form extract and raffinate phases, said raffinate phase containing less than ten per cent of said oil; separately recovering extract and raffinate from said extract and raffinate phases respectively; treating said raffinate with a ketone solvent to form a precipitate containing stabilizing agents; and adding a portion of said precipitate to said extract.

2. A method of refining soybean oil which includes the steps of: intimately contacting said soybean oil with a solvent having a critical temperature of less than 450° F. under liquefying pressure and in the paracritical range of the solvent-oil mixture to form extract and raffinate phases, said raffinate phase containing less than ten per cent of said oil; separately recovering extract and raffinate from said extract and raffinate phases respectively; treating said raffinate with a ketone solvent to form a precipitate containing stabilizing agents; separating said precipitate and

washing it with additional solvent selected from a group consisting of alcohols and ketones until additional washing produces no substantial lightening in color; and adding a portion of said washed precipitate to said extract.

3. A method of refining soybean oil which includes the steps of: intimately contacting said soybean oil with a solvent having a critical temperature of less than about 450° F. under liquefying pressure and in the paracritical range of the solvent-oil mixture to form extract and raffinate phases, said raffinate phase containing less than ten per cent of said oil; separately recovering extract and raffinate from said extract and raffinate phases respectively; treating said raffinate with ketone solvent to form a precipitate containing stabilizing agents; separating said precipitate and washing it with an alcohol; and adding a portion of said washed precipitate to said extract.

4. In the method of refining crude soybean oil which involves intimately contacting said oil with a solvent having a critical temperature of less than 450° F. under liquefying pressure and in the paracritical range of the solvent-oil mixture to form an extract phase containing substantially all of said oil and to precipitate a small raffinate phase containing substantially all color bodies and phosphatides, the improvement which includes the steps of: recovering decolorized soybean oil from said extract phase and treating said extract with steam to strip it of volatile components; treating the raffinate with an aqueous caustic solution and washing the remaining mixture with water to separate an oil scum from the water soluble constituents; and adding at least a portion of said oil scum to said steam treated soybean oil extract.

5. In the method of refining crude soybean oil which involves intimately contacting said oil with a solvent having a critical temperature of less than 450° F. under liquefying pressure and in the paracritical range of the solvent-oil mixture to form an extract phase containing substantially all of said oil and to precipitate a small raffinate phase containing substantially all color bodies and phosphatides, the improvement which includes the steps of: recovering decolorized soybean oil from said extract phase and treating said extract with steam to strip it of volatile components; treating said raffinate with a ketone solvent to form a precipitate containing stabilizing agents; separating said precipitate and washing it with additional solvent selected from a group consisting of alcohols and ketones until additional washing produces no substantial lightening in color; and adding a portion of said washed precipitate to said extract, said portion comprising less than one-tenth of one per cent of the original oil.

6. In the method of refining crude soybean oil which involves intimately contacting said oil with a solvent having a critical temperature of less than 450° F. under liquefying pressure and in the paracritical range of the solvent-oil mixture to form an extract phase containing substantially all of said oil and to precipitate a small raffinate phase containing substantially all color bodies and phosphatides, the improvement which includes the steps of: recovering decolorized soybean oil from said extract phase and treating said extract with steam in the temperature range between 350° F. and 450° F. for a period of between one and five hours with between five and twenty per cent of steam under a vacuum of between two and twenty mm. of mercury to strip it of volatile

components; treating said raffinate with a ketone solvent to form a precipitate containing stabilizing agents; separating said precipitate and washing it with additional solvent selected from a group consisting of alcohols and ketones until additional washing produces no substantial lightening in color; and adding a portion of said washed precipitate to said extract, said portion comprising less than one-tenth of one per cent of the original oil.

7. A method as described in claim 11 in which said bleaching agent is clay.

8. A method as described in claim 11 in which said bleaching agent is chlorine dioxide.

9. A method of refining soybean oil which includes: intimately contacting said soybean oil with a solvent having a critical temperature of less than about 450° F. under a liquefying pressure and in the paracritical range of the solvent-oil mixture in which the miscibility decreases as temperature increases, to form an extract phase containing most of the oil and a relatively small raffinate phase containing most of the color bodies from said soybean oil; separately withdrawing said extract and raffinate phases; returning not more than one tenth of said raffinate to said extract oil to produce an oil which is at least nine tenths decolorized and contains at least a portion of each raffinate stabilizing agent.

10. A method of refining soybean oil which includes: intimately contacting said soybean oil with a solvent having a critical temperature of less than about 450° F. under a liquefying pressure and in the paracritical range of the solvent-oil mixture in which miscibility decreases as temperature increases, to form an extract phase containing most of the oil and a relatively small raffinate phase containing most of the color bodies from said soybean oil; separately withdrawing

said extract and raffinate phases; separately treating the extract oil of said extract phase with steam to strip it of volatile components; dividing said raffinate into major and minor parts, said minor part amounting to less than one tenth of said raffinate; and adding said minor raffinate portion to said extract oil after said extract oil has been steam treated.

11. A method of refining soybean oil which includes: intimately contacting said soybean oil with a solvent having a critical temperature of less than about 450° F. under a liquefying pressure and in the paracritical range of the solvent-oil mixture in which miscibility decreases as temperature increases, to form an extract phase containing most of the oil and a relatively small raffinate phase containing most of the color bodies from said soybean oil; separately withdrawing said extract and raffinate phases; treating at least a part of said raffinate with a bleaching agent to lighten its color; and adding at least a part of said bleached raffinate to said extract oil.
